UNITED STATES PATENT OFFICE.

JAMES LEATHEM, OF LEBANON, PENNSYLVANIA.

ROTARY HOOK OR LOOP TAKER FOR SEWING MACHINES.

Application filed October 23, 1920. Serial No. 418,949.

To all whom it may concern:

Be it known that I, JAMES LEATHEM, a citizen of the United States, and a resident of Lebanon, in the county of Lebanon and State of Pennsylvania, have invented certain new and useful Improvements in Rotary Hooks or Loop Takers for Sewing Machines, of which the following is a specification.

10 This invention relates to rotary hooks or loop takers for sewing machines for lock stitch sewing machine mechanisms, and the objects of the invention are to simplify and improve the construction of such rotary hooks or loop takers and increase their efficiency of operation so that the same can be run at very high speeds.

The accompanying drawings illustrate one embodiment of my invention, in the several figures of which like parts are similarly designated.

In the drawings:

Figure 1 is a top view of a rotary hook or loop taker together with its bobbin case 25 and bobbin made in accordance with the present invention the drawing being on an enlarged scale for clearness of illustration.

Figure 2 is a sectional view on the line 2—2 of Figure 1 the drawing being on a 30 greater scale than Figure 1 for clearness of illustration.

Figure 3 is a top view of the bobbin case shown in Figure 1.

Figure 4 is a side view of the bobbin case shown in Figures 1 and 3.

Figure 5 is a sectional view of the bobbin case on the line 5—5 of Figure 3.

Figure 6 is a top view of the hook.

Figure 7 is a bottom view of the hook.

40 Figure 8 is a side view of the hook.

Figure 9 is a sectional view of the hook on the line 9—9 of Figure 6.

Figure 10 is a side view of the key.

In the drawings 1 designates a rotary hook or loop-taker of a lock stitch sewing machine mechanism, preferably made in one piece and provided with a beak 2 formed adjacent a beak recess 3. In the present instance the rotary hook is provided with a circular outer flange 4 having on its inner side adjacent the top thereof a circular groove or raceway 5 which is arranged to rotatably engage a circular bobbin case flange 6 made integral with a bobbin case 7.

55 In the present instance the hook flange

4 is integrally secured to the base of the hook at that portion of the hook flange immediately adjacent the beak 2, as shown in Figure 9, the remaining portions of the hook flange being cut away from the base 60 of the hook to permit the free end of the hook flange opposite the beak to be sprung out to admit the bobbin case flange 6 on the bobbin case into the raceway 5, as shown in Figure 2.

65 The free end of the hook flange while separated from the base of the hook preferably rests upon the same, as shown in Figures 2 and 8, to permit of suitable set screws 8 being used to firmly hold the free end of 70 the hook flange in position against the base of the hook after the bobbin case has been inserted.

75 The base of the hook is preferably provided with a circular hole 9 situated beneath the free end of the hook flange, in the present instance between the two set screws 8. The bottom edge of the hook flange is provided with a small hole 10 situated above the circular hole 9 and immediately 80 adjacent the edge thereof which acts to engage a small pin 11 of a suitable key 12 having a round portion 13 arranged to fit the circular hole 9, the pin 11 being set eccentrically on the round portion 13 of the 85 key so that it will act when turned to force the free end of the hook flange outward, when the set screws 8 have been removed, to permit of the easy removal or insertion 90 of the bobbin case.

95 The bobbin case 7 is a hollow cylindrical member, made in one piece, and having a centrally located post 14 adapted to receive a bobbin 15. In the present instance the bobbin case is provided with the usual lug 16 for engagement with a fixed part of the 100 sewing machine whereby rotation of the bobbin case is prevented. The bobbin case flange 6 on both sides of the lug 16 is cut away to permit of the beak 2 as it engages the bight or loop of the needle thread to carry the same inward so that the inner side of the bight or loop of the needle thread will be engaged by a loop flange 17 on the bobbin case. In the present instance the loop flange 105 17 is provided with a hooked shaped end 18, the same being preferably made integral with the bobbin case and made to project from the upper edge thereof, the hooked shaped end 18 being situated above the cut 110

away portion of the bobbin case flange 6 adjacent the lug 16 so as to engage the inner side of the bight or loop of the needle thread and so holding that side while the beak 2 in its rotation carries the other side of the bight or loop over the top of the bobbin case while the inner side of the bight or loop passes underneath the bobbin case to interlock with the bobbin thread.

10 The loop flange 17 in the present instance is cut or bent so that its upper and lower surfaces slope downward from the upper edge of the bobbin case, the outer edge of the loop flange 17 being arranged to pass just 15 inside and opposite a beak flange 19 which extends from the beak 2 to approximately half way around the hook flange 4, as shown in Figure 9. The beak flange 19 is cut on its outer edge to slope inward and acts to 20 guide the outer side of the bight or loop of the needle thread over the top of the bobbin case, the outer side of the bight or loop of the needle thread passing over the top of the bobbin case just previous to the time the end 25 of the beak flange 19 passes the hooked end of the loop flange 17. The beak flange 19 also acts as a guard to prevent the outer side of the bight or loop of the needle thread from engaging the loop flange 17, as the bight 30 or loop of the needle thread passes over the top of the bobbin case, the outer edge of the loop flange 17 being below the upper edge of the beak flange 19 and as its upper surface slopes upward to the top of the bobbin 35 case.

The bobbin case is provided with a bobbin thread tension device which in the present instance comprises a flat steel spring 20 one end of which is secured to the bobbin case, 40 above the bobbin case flange 6, by means of two small set screws 21. The other end of the tension spring 20 is provided on its upper edge with a small bobbin thread notch 22 which extends underneath the loop flange 17, the top edge of the tension spring in the 45 present instance being cut away to permit the notched end of the tension spring to engage the side of the bobbin case underneath the loop flange.

50 In the present instance the side of the bobbin case is provided with a bobbin thread slot 23 situated in back of and covered by the tension spring 20. The slot 23 extends from the upper edge of the bobbin case 55 diagonally downward to a point just above the bobbin case flange 6 along which it extends, the same terminating in a bobbin thread hole 24 which is spaced away from the thread notch 22 in the tension spring 20.

60 The bobbin thread 25 wound on the bobbin 15 is threaded through the tension device by drawing the bobbin thread down through the thread slot 23 to the thread hole 24 and forcing it in back of the free end of the tension spring 20 by drawing the bobbin thread 65

along the top of the tension spring until it reaches and passes out of the thread notch 22 near the end of the tension spring.

From the above description it will be seen that the bobbin thread passes from off the 70 bobbin and through the thread hole 24 which is situated approximately in the centre of the side of the bobbin case which facilitates a uniform pull of the thread from the bobbin. From the thread hole 24 the bobbin 75 thread passes up to the thread notch 22 between which points the thread is engaged by the tension spring 20 forcing the same against the side of the bobbin case. The tension of the spring 20 can be easily regulated by adjusting the inner set screw 21. The bobbin thread cannot come out of the 80 thread notch 22 as the top of the tension spring, adjacent the end of the notch, comes in contact with the under side of the loop 85 flange 17 which is also undercut so that the outer edge of the loop flange overhangs the top of the thread notch so as to further prevent the bobbin thread being pulled or slipped out of the notch 22.

90 The arrangement of the bobbin thread tension device makes it practically impossible for the bobbin thread once it is threaded therein to become displaced, the same is also very easily threaded, it being only necessary to 95 draw the thread into the thread slot 23 and then underneath the loop flange 17 where it will engage the thread notch 22, the rear end of the loop flange 17 being tapered toward the upper end of the thread slot 23 to accomplish 100 this purpose.

Due to the fact that the bobbin thread 105 tension device is situated on the side of the bobbin case a uniform pull on the bobbin thread is assured. It is further to be noted 110 that the position of the tension device under and adjacent the loop flange 17 assures that the same will not act to catch the outer side of the bight or loop of the needle thread as the same is protected by the beak flange 115 17 just previous to the time the outer side of the bight or loop passes over the top of the bobbin case.

The bobbin 15 is preferably made in one 120 piece as shown in Figure 2, the same being provided with a central bearing hole arranged to rotatably engage the bobbin case 125 post 14. Both ends of the bobbin bearing hole are slightly enlarged and undercut to form locking recesses 26 which are arranged 130 to be engaged by spring acting locking arms 27 secured to the top of the bobbin case post 14.

A locking recess 26 is provided on both 135 ends of the bobbin bearing hole as the bobbin is reversible and can therefore be locked in either position depending upon the direction of winding of the bobbin thread.

In the present instance the locking arms 140 27 form the circular bent ends of a spring 130

wire 28 the sides of which are arranged to loosely fit suitable vertical slots 29 formed in the sides of a pin 30 which is driven into position in the hollow end of the bobbin case post 14 to securely hold the spring wire 28 in place.

By referring to Figure 2 it will be seen that the top of the bobbin case post 14 and the top of the locking arms 27 are situated 10 below the top edge of the bobbin and will in no way interfere with the bight or loop of the needle thread passing over the same. It is also to be noted that the locking recesses 26 are so cut that either one will act 15 to force inward the locking arms 27 when the bobbin is placed over the bobbin case post 14 and either one of the recesses will also act to engage the locking arms 27 depending upon the direction of winding of 20 the bobbin thread on the bobbin which way the bobbin is placed in the bobbin case.

In order to remove the bobbin from the bobbin case it is usually customary to insert 25 a pointed tool or instrument into the upper recess 26 and pry the same with a slight lifting pressure upwards.

In order to overcome friction between the bobbin case and the hook the bobbin case flange 6 is preferably cut both top and bottom 30 as designated at 31 and 32 which are spaced at suitable intervals to correspond with the cut away portion of the bobbin case flange adjacent the lug 16.

The bobbin case flange 6 is also provided 35 with a series of radial slots 33 which act to hold oil to lubricate the groove or raceway 5.

In the present instance the base of the hook is integrally secured to a shaft 34 40 which can be mounted in a suitable bearing and secured to a suitable gear not shown for rotating the same.

The rotary hook or loop taker above described is adapted for use in my copending 45 sewing machine application Serial No. 410,472, filed September 15, 1920, and is capable of being rotated at a speed of nine thousand revolutions a minute upward to ten thousand revolutions a minute.

50 While the invention has been described with particular reference to the details of construction the same is not to be considered as limited thereto, as many changes can be made and still fall within the scope of the 55 invention set forth in the following claims.

What I claim is:

1. A rotary hook or loop taker for sewing machines comprising a hook, a hook flange, a bobbin case, said flange and bobbin case having interlocking means to prevent the separation of the same and allow of the rotation of the bobbin case in the flange, and means for allowing the flange to be sprung in a plane at right angles to the 60 axis of the rotary hook or loop taker.

2. A rotary hook or loop taker for sewing machines, comprising a hook, a hook flange having a race way therein, a bobbin case, a beading on said bobbin case fitting in said race way and means for allowing the flange 70 to be swung in a plane at right angles to the axis of the rotary hook or loop taker to allow the bobbin case to be removed in a plane parallel the axis of the rotary hook or loop taker.

75 3. A rotary hook or loop taker for sewing machines, comprising a hook having a beak, a hook flange secured to said hook adjacent said beak, a raceway in said hook flange, a bobbin case, a bobbin case flange 80 on said bobbin case, the free end of said hook flange being arranged to be sprung to admit the bobbin case flange on the bobbin case into engagement with the raceway in said hook flange.

85 4. A rotary hook or loop taker for sewing machines, comprising a hook, a hook flange secured at one end to said hook, a raceway in said hook flange, a bobbin case, a bobbin case flange 90 on said bobbin case, the free end of said hook flange being arranged to be sprung to admit the bobbin case flange on the bobbin case into engagement with the raceway in said hook flange, 95 hook flange after said bobbin case has been inserted in the raceway in said hook flange.

5. A rotary hook or loop taker for sewing machines, comprising a hook having a beak, a hook flange secured to said hook 100 adjacent said beak, a raceway in said hook flange, a bobbin case, a bobbin case flange on said bobbin case, the free end of said hook flange being arranged to be sprung to admit the bobbin case flange on the bobbin case 105 into engagement with the raceway in said hook flange, and means for locking the free end of said hook flange after said bobbin case has been inserted in the raceway in said hook flange.

110 6. A rotary hook or loop taker for sewing machines comprising a hook, a hook flange, a raceway in said hook flange, a bobbin case, a bobbin case flange on said bobbin case, means for connecting said hook flange to said hook to permit of the same being sprung to admit the bobbin case flange on the bobbin case into engagement with the raceway on said hook flange, and means on said hook to permit of the same being 115 sprung to admit or remove the bobbin case.

120 7. A rotary hook or loop taker for sewing machines comprising a hook, a hook flange secured at one end to said hook, a raceway in said hook flange, a bobbin case, 125 a bobbin case flange on said bobbin case, the free end of said hook flange being arranged to be sprung to admit the bobbin case flange on the bobbin case into engagement with the raceway in said hook flange, 130

- and means on said hook to permit of the same being sprung to admit or remove the bobbin case.
8. A rotary hook or loop taker for sewing machines comprising a hook having a beak, a hook flange secured to said hook adjacent said beak, a raceway in said hook flange, a bobbin case, a bobbin case flange on said bobbin case, the free end of said hook flange being arranged to be sprung to admit the bobbin case flange on the bobbin case into engagement with the raceway in said hook flange and means on said hook to permit of the same being sprung to admit or remove the bobbin case.
9. A rotary hook or loop taker for sewing machines, comprising a bobbin case, a loop flange on said bobbin case, and a bobbin thread tension device secured to said bobbin case, said bobbin thread tension device being arranged to extend underneath said loop flange and having a thread notch therein.
10. A rotary hook or loop taker for sewing machines, comprising a bobbin case, a loop flange having a hooked shaped end on said bobbin case, and a bobbin thread tension device arranged to engage the underside of said loop flange.
11. A rotary hook or loop taker for sewing machines comprising a bobbin case, an undercut loop flange on said bobbin case, and a bobbin thread tension device having a thread notch arranged to engage the undercut side of said loop flange.
12. A rotary hook or loop taker for sewing machines, comprising a bobbin case, a loop flange secured to the side of said bobbin case, a thread slot situated in the side of said bobbin case adjacent said loop flange, a thread tension spring secured at one end to the side of said bobbin case, the side of said thread tension spring being arranged to cover and extend beyond the end of said thread slot; the free end of said thread tension spring being provided with a thread notch, which extends underneath the underside of said loop flange.
13. A rotary hook or loop taker for sewing machines, comprising a bobbin case, a thread slot in the side of said bobbin case, a thread tension spring secured at one end to said bobbin case, the side of said thread tension spring being arranged to cover and extend beyond the end of said thread slot, a thread notch in the end of said thread ten-
- sion spring, and means on said bobbin case for engaging said thread notch.
14. A rotary hook or loop taker for sewing machines comprising a hook flange having a hook and a free end, a bobbin case, said bobbin case and flange having interlocking beading and raceway, said free end of the flange adapted to be sprung at right angles to the axis of the hook or loop taker, and means for springing the free end of the flange.
15. A rotary hook or loop taker for sewing machines, comprising a hook flange having a hook and a free end, a bobbin case, interlocking means between the bobbin case and the hook flange, said free end of the hook flange adapted to be sprung at right angles to the axis of the hook or loop taker for allowing the bobbin case to be removed or inserted and means for springing the free end of the flange.
16. A rotary hook or loop taker for sewing machines, comprising a hook flange having a hook and a free end, a bobbin case, interlocking means between the bobbin case and the hook flange, said free end of the hook flange adapted to be sprung at right angles to the axis of the loop taker for allowing the bobbin case to be removed or inserted and means operated by a removable key for springing the free end of the flange.
17. A rotary hook or loop taker for sewing machines comprising a hook flange having a hook and a free end, a bobbin case, said bobbin case and flange having interlocking beading and raceway, and said free end of the flange adapted to be sprung at right angles to the axis of the hook or loop taker.
18. A rotary hook or loop taker for sewing machines comprising a hook flange having a hook and free end, a bobbin case, and interlocking means between the bobbin case and the hook flange, and said free end of the hook flange adapted to be sprung at right angles to the axis of the hook or loop taker for allowing the bobbin case to be removed or inserted.
